UNITED STATES PATENT OFFICE.

WENDELL A. BARKER, OF ELKHART, INDIANA.

REVOLVING-JAW CHUCK.

1,373,789.

Specification of Letters Patent.

Patented Apr. 5, 1921.

Application filed November 19, 1919. Serial No. 339,080.

To all whom it may concern:

Be it known that I, WENDELL A. BARKER, a citizen of the United States, residing at Elkhart, in the county of Elkhart and State 5 of Indiana, have invented certain new and useful Improvements in Revolving-Jaw Chucks, of which the following is a specification.

This invention relates to improvements in 10 chucks of that general type wherein the workholding elements of the chuck are so designed and constructed that they may be moved bodily into and out of gripping engagement with the work, and may also be 15 turned to a greater or less extent so as to bring different surfaces of the work into position to be machined without the necessity of readjusting the work in the chuck jaws.

20 The general purposes or objects of the present invention is to provide a chuck of the revolving jaw type equipped with improved means by which the workholding elements may be indexed by the simple manipulation of a hand lever, and when indexed to the desired extent shall be automatically locked in the new position.

Another object is to provide a chuck of 30 the revolving jaw type wherein, through the use of interchangeable elements, which control and determine the extent of the indexing movement, the work-holding elements may be indexed to practically any desired extent within limits of a few degrees.

35 A still further object of the invention is to provide, in combination with the indexing and locking mechanism, a manually operable actuating mechanism for said indexing mechanism based upon the same principle of operation as that described in my former Patent No. 1,249,300, Dec. 11, 1917, for effecting the in and out radial movements of the jaws of a chuck either when the chuck is idle or when it is rotating.

45 Other more specific objects and advantages of the present invention will be apparent to those skilled in the art as the same becomes better understood by reference to the following detailed description and the 50 accompanying drawings, wherein I have illustrated one practical embodiment of the principle of the invention and in which—

Figure 1 is an elevation, partly in vertical section, of a chuck having a pair of diametrically opposed jaws, showing my improved revolving workholders and their in-

dexing mechanism, and the means for actuating said indexing mechanism; the workholders being shown in locked position;

Fig. 2 is a similar view, showing the 60 workholder unlocked and indexed to another position;

Fig. 3 is a front elevation, partly in section, of the parts shown in Figs. 1 and 2; taken on line 3—3 of Fig. 1. 65

Fig. 4 is a top view, looking downwardly on one of the chuck jaws;

Fig. 5 is a horizontal section taken on the line 5—5 of Fig. 1;

Fig. 6 is a detailed plan view of one of the 70 notched indexing rings, designed to index the workholding elements of the jaws through one hundred and eighty degrees;

Fig. 7 is a similar view of a substitute 75 indexing ring designed to index the workholders through ninety degrees;

Fig. 8 is a perspective detail of the indexing pins and their actuating springs which coöperate with the rings shown in Figs. 6 and 7. 80

Fig. 9 is a detail elevation of the revolving workholder or jaw clamp; and

Fig. 10 is a detail elevation, partly in vertical section, of a slidable member which locks and unlocks the revoluble workholder 85 and carries the indexing pins shown in detail in Fig. 8.

Referring to the drawings, 5 indicates a spindle of a lathe upon which the hub 6 of a chuck body designated generally by reference character 7 is threaded in the usual manner as shown in Figs. 1 and 2. On the face of a chuck body are diametrically opposed pairs of radial slideways 8 (Figs. 4 and 5), in each of which is slidably mounted a hollow jaw casting designated as an 90 entirety by 9. These jaw castings are actuated toward and from the axial line of the chuck body by a mechanism substantially like that described in my former Patent 100 1,249,300, aforesaid. Briefly describing this mechanism, surrounding the hub 6 of the chuck body is rotatably mounted a cam disk 10 in the face of which are a pair of cam grooves 11 that are engaged by rollers 12 105 mounted on studs 13 which are tapped into the jaw castings 9 as clearly shown in Figs. 1 and 2, whereby a turning movement of the cam disk 10 in one direction moves the cam jaws outwardly, and a turning movement of said disk in the opposite direction moves the cam jaws inwardly. On the hub 110

of the cam disk 10 is formed a gear 14. A gear 15 of the same size and number of teeth is rigidly secured by a key 16 or other suitable means to the outer end of the chuck 5 hub 6 so as to rotate therewith. The gear 15 has a sleeve extension 17, on which and on the hub of the cam disk 10 just forwardly of the gear 14, is rotatably mounted a gear cage comprising a pair of rings 18 and 19 that are integrally spaced and connected by crossbars. In this gear cage are mounted on pins 20 four pairs of planet gears, each pair consisting of a gear 21 meshing with the gear 15 and a gear 22 meshing with the cam gear 14, said gears 21 and 22 being independently journaled on the bearing pin 20. 23 designates a stationary annular rear wall, the inner periphery of which fits over a short hub 24 on the cage 15 ring 18. The outer periphery of the stationary wall 23 is formed as a forwardly extending flange 25 on which is formed an internal gear 26 meshing with the planet gears 21. Mounted with capacity for a 25 turning movement on the cage ring 19 is a ring 27 provided on its upper side with a radially projecting handle 28 by which said ring can be manually turned in either direction. On the inner periphery of the ring 27 is an internal gear 29 of the same size and number of teeth as the internal gear 26 and meshing with the planet gear 22. A clamping nut or ring 30 is threaded on to the rear end of the chuck hub 6 to prevent 35 accidental escape of the key 16 and to assist in uniting the parts and steadyng the construction. Assuming now that the chuck is rotating, the gear 15 will be rotated with the hub 6 of the chuck and by 40 reason of the intermeshing relation of the planet gears 21 with the rotating gear 15 and the stationary internal gear 26, the gear cage will be rotated in the same direction as the chuck but at a slower speed. As the 45 gear cage rotates, carrying with it the planet gears 22, each of which meshes with the cam gear 14 and the internal gear 29 which normally is stationary relatively to the internal gear 26, the cam disk 10 will 50 be rotated in the same direction as the chuck and at the same speed. Since the jaw operating studs 13 are carried around by the chuck in the same direction and at the same speed as the cam disk, it is manifest 55 that no relative movement between the cam disk and the studs takes place, and consequently the jaws remain stationary relatively to the chuck body. When it is desired to open or close the chuck jaws, the 60 handle 28 is swung toward or from the operator. This, through the internal gear 29 either accelerates or retards the bodily travel of the planet gears 22, as a result of which a relative turning movement of the 65 cam disk 10 either faster or slower than the

turning movement of the chuck body is set up, in consequence of which, through the action of the cam groove 11 on the rollers or followers 12, the jaws are moved inwardly or outwardly during the swinging movement of the handle 28. At the conclusion of such swinging movement, the jaws at once become stationary relatively to the chuck body. 70

The above described mechanism for actuating the chuck jaws inwardly and outwardly is substantially like that disclosed in my former patent above referred to, with the exception of the particular form of cam and cam actuated connections to the 75 jaws. In the preferred embodiment of my present invention I have adopted a mechanism operating on this same principle for actuating the indexing mechanism of the revolving workholders or clamps mounted 80 in and carried by the radially movable jaws of the chuck, and this actuating mechanism will next be described. 85

Referring to Figs. 1 and 2, 31 designates a ring gear of the same size and number of 90 teeth as the gears 14 and 15 and revolubly mounted on the hub 6 between the latter. This gear 31 meshes with planet gears 32 which are journaled on the pins 20 between the planet gears 21 and 22. These planet 95 gears 32 in turn mesh with an internal gear 33 formed on a ring 34 which is mounted with capacity for turning movement on the stationary annular rear wall 23, and is provided on its upper side with a radially projecting handle 35, by which said ring can be manually turned in either direction. When the handle 35 is swung in one direction, a relative movement of the ring gear 31 to the hub 6 of the chuck in one direction 100 takes place; and when the handle 35 is swung in the opposite direction a similar relative movement of the ring gear 31 takes place in the opposite direction. In other words, manipulation of the handle 35 effects 105 relative movement of the gear ring 31 to the hub of the chuck in the same way that manipulation of the handle 28 effects relative movement of the cam disk 10 to the hub of the chuck. Integral with the ring 31 is a 110 sleeve 36 that has extended bearings on the hub 6 of the chuck and lies between the latter and the hub of the cam disk 10. The free end of the sleeve 36 is formed as a gear ring 37, best shown in Fig. 5. 115

Passing now to a description of the revoluble elements of the chuck jaws, which I have termed the revoluble workholders or clamps, 38 designates a circular disk or plate that slidably fits the inner wall of the lower 120 portion of the hollow jaw casting 9 and is formed on its lower face with a diametric groove or channel 39 designed to receive the false jaws usually employed in revolving jaw chucks for engaging with the work. On 130

and preferably integral with the plate or disk 38 is a central vertical stem comprising a lower portion 40, an intermediate reduced portion 41 providing an annular shoulder 42 (Fig. 9) at the upper end of the lower portion 40, and an upper reduced threaded portion 43. On the disk 38 is an upstanding circular flange 44, on the upper edge of which are formed a circular row of substantially rectangular teeth 45. In the flange 44 are a series, herein shown as four, of oblique slots 46 extending from the upper toothed edge of the flange to approximately its mid-height, and all being inclined in the same direction. This member shown in isolated detail in Fig. 9 is rotatably mounted within the hollow jaw casting 9; the intermediate portion 41 of its stem being journaled in a bearing sleeve 47 that is externally threaded 20 and mounted within a tapped bore 48 in the upper portion of the jaw casting and locked by a nut 47'. The upper end of the bearing sleeve 47 is countersunk to accommodate a washer 49 and a nut 50 on the threaded end 25 43 of the stem, by which the revolving workholder or clamp is supported within the jaw housing. Between the shoulder 42 and the lower end of the bearing sleeve 47 is interposed an antifriction thrust bearing 51. 30

Surrounding the circular flange 44 is a wide gear ring 52, which meshes with and is driven by the large gear ring 37, as most clearly shown in Fig. 5. This ring carries 25 four inwardly projecting radial studs 53 which lie within the oblique slots 46 of the flange 44. Within the flange 44 and non-rotatably and removably secured thereto by a pair of oppositely disposed pins or studs 54, is an indexing ring 55, shown in detail in Figs. 6 and 7. This ring has on its inner periphery a groove or channel 56 formed 40 with an oblique upper wall, as shown in Figs. 1 and 2. This ring is further provided with a plurality of vertical notches 57 extending from the upper side of the ring through the upper wall of the groove or channel 56. These indexing rings constitute removable and interchangeable elements of the machine, and the notches 57 may be spaced, within practical limits, anywhere from five degrees to one hundred and eighty degrees apart, depending upon the angular extent to which any given piece of work may require to be indexed. In Fig. 6 I have shown the ring 55 equipped with a pair of notches 57 located one hundred and eighty degrees apart. In Fig. 7 I have shown the ring equipped with four notches 57 located ninety degrees apart. Obviously, other rings may be used having notches spaced five degrees or any multiple of five degrees apart. The spacing of these notches determines the angular extent to which the work is indexed at each indexing operation. 55

Within the jaw-housing and lying mainly within the flange 44 of the work-clamp or jaw is a device which has the function of locking the work-clamp or jaw in any position to which it may have been indexed. 70 This device is shown in isolated detail in Fig. 10, and comprises the following parts, 58 designates a cup shaped member having a central aperture 59 by which it is slidably mounted on the lower portion 40 of the 75 stem of the revoluble work clamp or jaw. The device 58 is provided on its upper edge with a radial flange 60 that, in the lowermost position of the device, overlaps the upper edge of the large gear ring 52, as clearly 80 shown in Fig. 1. On the under side of the flange 60 is an annular row of depending gear teeth 61 that coöperate with the gear teeth 45 of the flange 44 in a manner hereinafter described. A coil spring 62 surrounding the lower portion 40 of the stem of the revoluble jaw and confined endwise between the thrust bearing 51 and the bottom of the cup shaped member 58 normally urges the latter toward its lowermost position shown in Fig. 1. The base of the cup shaped member 58 is formed with a pair of oppositely disposed slideways 63, and with an annular groove 64 in the wall of the central hole 59. Within the slideways 63 are 90 mounted a pair of pins 65, shown in isolated detail in Fig. 8, these pins 65 having pointed ends 65' that, in the locked position of the jaw shown in Fig. 1 lie in the groove or channel 56 of the ring 55, and in the unlocked position of the jaw shown in Fig. 2 rest upon the upper side of said ring. The pins 65 are connected and normally urged outwardly by an elastic spring ring 66 that is seated in the annular groove 64. Tapped 105 into the flange 60 of the locking member 58 are a series of vertical pins 67 that slidably engage with vertical holes in the upper portion of the jaw casting, as clearly shown in Fig. 3, to hold the locking member 58 non-110 rotatable, while permitting a limited outward and inward movement thereof.

Describing the operation of the complete apparatus, when a piece of work is to be placed in the jaws of the chuck, false jaws 115 (not shown) if necessitated by the size of the work, are fitted in the cross grooves or channels 39 of the revoluble jaw, and the handle 28 is swung in the proper direction to effect an inward or work-clamping movement of the jaws upon the work. This may be done either when the chuck is idle or when it is rotating. When the surface of the work presented to the cutting tool of the lathe has been sufficiently machined, and 120 it is desired to machine another surface of the work, the handle 35 is pushed in a direction from the observer viewing Fig. 1, and this causes a rotation of the gear rings 37 and 52 in a direction toward the ob- 125 65

server at the point where said gears mesh. As the gear ring 52 rotates, the pins or studs 53 carried thereby ride upwardly in the cam slots 46 of the flange 44, thereby causing the ring 52 to rise bodily and carry with it the locking member 58 to release position, this position of the parts being shown in Fig. 2. As the locking member 58 rises, compressing the spring 62, the sliding pins 65 are forced inwardly by reason of the inclined upper side of the annular groove 56 of the ring 55 until, when the points of said pins have passed above the ring 55, the spring 66 forces them outwardly into overlapping relation with the ring 55, as shown in Fig. 2. The revolving jaw is now unlocked, and ready to be indexed to the next position. This is done by swinging the handle lever 35 in the opposite direction or toward the observer viewing Fig. 1, which sets up a rotation of the ring 52 in the opposite direction. With the locking device held in unlocking position by the pins 65 resting on the ring 55, the ring 52 descends until the studs 53 strike the bottoms of the inclined slots 46, and thereafter the jaw itself revolves with the ring 52 until a pair of oppositely disposed notches 57 come into register with the ends 65' of the pins 65. The ends of the said pins thereupon drop into and through the notches 57, and this lowers the locking device 58 to a point at which the upper row of teeth 61 come to rest upon the lower row of teeth 45; and thereupon a slight additional rotation of the jaw brings the lower teeth 45 into full register with the spaces between the upper teeth 61, and the locking device drops slightly farther to a point at which the two rows of teeth are fully interlocked and the points 65' of the pins 65 lie on the bottom wall of the annular groove or channel 56 slightly beyond the notches 57 through which they dropped. If the ring 55 has only a pair of indexing notches 57, as shown in Fig. 6, the work will be indexed through one-half a revolution, or one hundred and eighty degrees. If the ring has four indexing notches spaced ninety degrees apart, as shown in Fig. 7, the jaw will be indexed through ninety degrees. With the indexing and locking mechanism herein shown, it is practical to employ indexing rings 55 carrying notches spaced as closely as five degrees apart.

The purpose of providing the adjustable bearing sleeve 47 for the revoluble jaw is to make a small allowance for adjustment to correct any mismeasurement in making the false jaws to fit the piece to be machined. In practice, an adjustment of approximately one fourth of an inch is sufficient, and the adjustment is effected by loosening the lock-nut 47', applying a spanner to the bearing sleeve 47, adjusting the latter inwardly or

outwardly to the required extent, and then tightening up the lock-nut 47.

From the foregoing it will be seen that by the use of this invention, it is possible to rotate the work so as to bring a new surface in position to be machined by the simple manipulation of the handle lever 35, and without stopping the rotation of the spindle or chuck. So far as I am aware, there has heretofore been no means for effecting this turning movement of the revoluble work clamps or jaws except by a hand wrench after the chuck has been stopped and a lock-bolt withdrawn, or a thumb latch operated by hand to allow the work clamp or jaw to revolve. By the use of my present invention no wrench or other tool is required to index the jaws, nor is it even necessary to stop the rotation of the chuck. By merely swinging the handle lever 35 in one direction, the locking device of the revolving jaw is retracted, and by then swinging the said handle lever in the reverse direction the jaw is indexed to the required or desired extent and automatically relocked in its new position.

From the foregoing description it will be seen that in my present invention I have not only provided a simple and effective means for indexing a pair of revoluble chuck jaws through the manipulation of a single hand lever whether the chuck be rotating or idle, but I have also combined such a mechanism in a convenient manner with a lever operated mechanism for effecting the radial work-gripping and releasing movements of the jaws substantially like that disclosed in my former patent above referred to, thereby extending the benefits and advantages of the jaw actuating mechanism of the said patent to chucks of the revolving jaw type.

It will be evident to those skilled in the art that the specific mechanism herein shown and described may be modified and varied in detail without departing from the operative principle involved or sacrificing any of the advantages inherent in the invention. Hence, I reserve all such variations and modifications as fall within the spirit and purview of the appended claims.

I claim—

1. In a chuck of the character described, the combination of a rotatable chuck body, a radially movable jaw housing mounted on said chuck body, a rotatable jaw mounted in said housing and formed with an annular row of teeth on its outer side, a locking member for said jaw slidably mounted in said housing and formed with an annular row of teeth movable into and out of locking engagement with the teeth of said jaw, a spring urging said locking member into locking engagement with said jaw, a rotatable member mounted in said housing and

5 serving when turned in one direction to retract said locking member and when turned in the opposite direction to index said jaw to a new position, and manually operable means mounted on said chuck body for actuating said rotatable member in both directions.

2. In a chuck of the character described, the combination of a rotatable chuck body, 10 a radially movable jaw housing mounted on said chuck body, a rotatable jaw mounted in said housing, a locking device for said jaw slidably mounted in said housing, a spring normally urging said locking device 15 into locking engagement with said jaw, a rotatable member mounted in said housing and serving when turned in one direction to retract said locking device and when turned in the opposite direction to index 20 said jaw to a new position, manually operable means mounted on said chuck body for actuating said rotatable member in both directions, and coöperating means carried by said jaw and said locking device serving 25 to hold the latter inoperative during the indexing movement and to determine the extent of the indexing movement.

3. In a chuck of the character described, the combination of a rotatable chuck body, 30 a hollow jaw housing mounted on said chuck body, a rotatable jaw mounted in said housing, means for moving said housing radially of said chuck body, a rotatable gear ring surrounding and drivingly connected to said 35 jaw, a sleeve rotatably mounted on said chuck body co-axially with the latter and formed on one end with a gear ring meshing with said first-named gear ring, and manually operable means mounted on said 40 chuck body for turning said sleeve.

4. In a chuck of the character described, the combination of a rotatable chuck body, a hollow jaw housing mounted on said chuck body, a rotatable jaw mounted in said housing, 45 means for moving said housing radially of said chuck body, a locking member for said jaw slidably mounted in said housing and movable into and out of locking engagement with said jaw, a rotatable gear ring surrounding said jaw, said gear ring when turned in one direction operating to retract said locking member and when turned in the opposite direction operating to index said jaw, a sleeve rotatably mounted on said 50 chuck body co-axially with the latter and formed on one end with a gear ring meshing with said first-named gear ring, and manually operable means mounted on said 55 chuck body for turning said sleeve.

60 5. In a chuck of the character described, the combination of a rotatable chuck body, a hollow jaw housing mounted on said chuck body, a rotatable jaw mounted in said hous-

ing and formed with an annular flange provided with a cam slot and a toothed upper 65 edge, a gear ring surrounding said flange and carrying a stud engaged with said cam slot, a locking member slidably mounted in said housing and formed with teeth adapted to interlockingly engage with the toothed 70 upper edge of said flange and with a flange overlying said gear ring, a spring normally urging said locking member into locking position, and means mounted on said chuck body for actuating said gear ring in one direction to retract said locking member and in the opposite direction to index said jaw to a new position.

6. In a chuck of the character described, the combination of a rotatable chuck body, 80 a hollow jaw housing mounted on said chuck body, a rotatable jaw mounted in said housing and formed with an annular flange provided with a cam slot and a toothed upper 85 edge, a gear ring surrounding said flange and carrying a stud engaged with said cam slot, a locking member slidably mounted in said housing and formed with teeth adapted to interlockingly engage with the toothed 90 edge of said flange and with a flange overlying said gear ring, a spring normally urging said locking member into locking position, means mounted on said chuck body for actuating said gear ring in one direction to retract said locking member and in the opposite direction to index said jaw to a new 95 position, and coöperating means carried by said jaw and said locking device serving to hold the latter inoperative during the indexing movement and to determine the extent 100 of the indexing movement.

7. In a chuck of the character described, the combination of a hollow jaw housing, a jaw rotatably mounted in said housing and formed with an annular flange provided 105 with a cam slot and toothed upper edge, a gear ring surrounding said flange and carrying a stud engaged with said cam slot, a locking member slidably mounted in said housing and formed with teeth adapted to 110 interlockingly engage with the toothed edge of said flange and with a flange overlying said gear ring, a spring normally urging said locking member into locking position, an internally grooved indexing ring mounted 115 within said flange and formed with notches in the upper wall of its groove, and sliding outwardly spring-pressed pins mounted in said locking device and having their outer ends lying in the groove of said 120 indexing ring, said pins overlying and resting upon said indexing ring when said locking device is retracted and coöperating with said notches to determine the extent of indexing movement of said jaw.

WENDELL A. BARKER.
